STEAM GENERATING SYSTEM

Chadwell O'Connor, Los Angeles, Calif.

Application March 4, 1939, Serial No. 259,720

15 Claims. (Cl. 122—245)

This invention relates to a novel steam generating system and more particularly concerns a novel water tube steam generating unit and an improved method of generating steam.

One object of the invention is to provide a novel method of and apparatus for generating steam including an improved steam generating unit of the water tube type adapted to be operated at substantially higher thermal efficiency than has heretofore been practicable.

Another object is to provide an improved steam generating unit capable of operating at high and substantially uniform efficiency at any rate within its capacity.

Another object is to provide a steam generating unit of the water tube type in which stagnation of water at the heating surfaces and consequent overheating of the latter is avoided.

Still another object is to provide a steam generating unit of the above general character in which sedimentation or deposit of scale from the water upon the heating surfaces is materially reduced or substantially eliminated, thereby greatly increasing the length of service of the heating surface without shutdown for cleaning and substantially prolonging the life thereof.

Another object is to provide an improved steam generating unit of the water tube type in which the various parts subjected to heat are maintained at substantially uniform temperatures when the unit is in operation, thus avoiding excessive strains due to unequal expansion with attendant weakening of the parts.

The foregoing objects are attained by reason of the novel and advantageous construction of the steam generating unit together with the provision of means for effecting circulation of water over the heat transfer surfaces at a substantially higher velocity than is attainable by convection alone. More particularly, maximum efficiency as well as other advantages including those above set forth are attained by arrangement of the heat transfer surface and water circulating means in a manner such that the water in association with such surfaces is under sufficient pressure to maintain its critical temperature above actual water temperature to minimize steaming at this point, while the water is circulated over the heat transfer surfaces at such a velocity and in such volume that not more than one part in three of any unit volume of the water is converted into steam upon its discharge into the steam chamber of the unit. By thus maintaining water rather than steam in contact with

the heat transfer surfaces, heat absorption is effected with great efficiency.

Still another object of the invention resides in the novel method of and means for separating the steam from the water without surging, agitation or foaming even though circulation in the system has been greatly accelerated.

A further object of the invention is to provide a boiler of compact, easily accessible construction which will efficiently utilize not only convected heat but also radiated heat and in which heat loss is maintained at a minimum. Ancillary to this, it is an object to provide a construction such that even the heat escaping from the auxiliary equipment such as pumping mechanism and connecting pipes is utilized, as for preheating the air supply for the burners.

A still further object of the invention is to provide a novel boiler assembly wherein all parts are readily accessible with a minimum of interference from or disturbance of adjacent or co-acting parts and in which replacements can be effected easily and quickly.

It is also an object of the invention to provide a highly efficient arrangement of heating tubes adapted for high velocity circulation of the water therethrough without the creation of back pressure as steaming progresses, heat being abstracted with high efficiency from the combustion gases passing between the coils in such a manner that the heat is transferred to the water in a uniform, progressive manner. An ancillary object is to mount the heating coils in an improved manner to permit individual coil sections to be removed from and replaced in the assembly quickly and easily.

Additional objects of the invention are to provide an improved multiple section insulated casting for enclosing the boiler designed to permit removal of individual sections for access to selected portions of the installation; to provide an improved water and steam chamber which will serve in addition as a mud drum, preheater and steam separating chamber; to provide improved means for effecting forced circulation in the system; and to provide a vertical boiler structure of industrial capacity requiring only very low headroom and very limited floor space, which will avoid the necessity for special settings or boiler pit and which is adapted to receive most of the auxiliary equipment within a raised base below the main superstructure of the steam generating mechanism.

Other objects and advantages will become ap-

parent in the following description and from the accompanying drawings in which:

Figure 1 is a side elevational view, partially in section, showing a steam generating unit embodying the principles of the invention.

Fig. 2 is a vertical sectional view through the unit taken substantially along line 2—2 of Fig. 1, and having certain electrical features shown schematically.

Fig. 3 is an enlarged perspective view of one 10 of the hangers used in suspending the heating coils.

Fig. 4 is a top sectional plan view of the unit taken substantially in the plane of line 4—4 of Fig. 2.

Fig. 5 is a side elevational view of the unit, partially broken away, showing a modification.

Fig. 6 is a fragmentary side elevational view of the upper portion of the unit, partially in section showing a further modification.

Fig. 7 is a sectional plan view taken substantially on the plane of line 7—7 of Fig. 6.

While the invention is susceptible of various modifications and alternative constructions, I have shown in the drawings and will herein describe in detail selected preferred embodiments, but it is to be understood that I do not thereby intend to limit the invention to the specific forms disclosed, but intend to cover all modifications and alternative or variant constructions and systems falling within the spirit and scope of the invention as expressed in the appended claims.

As a matter of convenience the terms "water" and "steam" have been used herein to designate the liquid medium which is converted into gaseous form in the operation of the system, but these terms are intended to be generic and not restrictive in meaning and should be construed wherever possible, consistent with practicability, as covering any liquid medium that can be used for this purpose and its gas or vapor which will be formed in the practice of the method or use of the apparatus disclosed.

Generally speaking, the novel steam generating system of the present invention includes in a continuous cycle the steps of withdrawing water from a partially filled storage chamber or drum within which it may be thoroughly preheated, impelling the withdrawn water into circulation in contact with heat transfer surfaces, returning the heated water to the chamber to permit expansion and conversion of a portion thereof to steam, and therein effecting separation of the steam and commingling of the unconverted water with make-up water, and recirculating the water in contact with the heat transfer surfaces. Preferably, the velocity with which the water is circulated and its pressure, while in contact with the heat transfer surfaces, is such that only about one-third or less of the water is converted into steam upon its discharge into the steam chamber. In returning the water and generated steam to the drum, the steam is substantially all withdrawn in the upper water-free part of the chamber before the heated water is returned to the body of water therein, thereby relieving pressure from and avoiding gushing of the returned water and preventing agitation and foaming in the body of water. In addition to preheating of the substantially constant head of the body of water in the drum by external means, the heated water which is separated from the steam and returned to the drum in the circulation cycle will serve as a preheating medium.

The invention may be practiced in connection

with and embodied in a preferred practical form of steam generating unit or boiler as shown by way of illustration in Figs. 1 to 4, inclusive, including an elongated vertical water and steam tank or drum 15 mounted centrally upon a base framework 16. Water is conducted from the drum 15 under forced circulation through a pressure duct 17 to a series of heating tubes, indicated generally by the numeral 18, located about the upper portion of the drum 15 above and within the heating zone of a suitable source of heat such as a plurality of any preferred form of gas burners 19. In the heating tubes 18 the water is raised to a temperature suitable for converting a portion into steam, the conversion into steam taking place upon its discharge into the upper part of the drum 15. A separator 20 acts to bleed off or separate the steam from the water.

Herein the drum 15 serves the multiple functions of water reservoir, preheater, mud drum, separating chamber and steam chest, thereby effecting substantial structural and space economy in the unit. Preferably a seamless cylindrical construction is employed in the drum 15, the ends being suitably closed as by swaging, although heads could be secured to the ends of the tube body as by welding. The drum ends are preferably of concavo-convex shape to provide a dome 15^a at the top and a dished bottom 15^b which may serve as a mud sump. Access into the drum may be had through one or more removable clean out plugs 21 located adjacent to the bottom 15^b. Periodic cleaning out of mud deposited in the bottom 15^b may be effected through a valve controlled blow-off 22 leading from the pit of the bottom.

Any suitable means may be provided for supporting the drum 15 upon the base framework 16, an annular cradle 23 herein serving such purpose and preferably being secured fixedly to the lower end of the drum as by welding. The cradle 23 may have connecting flanges 24 by which it can be secured detachably to a top platform 25 upon the base 16, the flanges being held down by bolts 26 so that when desired the drum 15 may be removed from the base.

In the preferred form, the base framework 16 is constructed of structural iron members suitably connected as by welding. In this framework, the top platform 25 is preferably supported by uprights or legs 27 in raised relation to a surface such as a floor 28 upon which the unit may be supported. Through this construction a substantial chamber is provided below the top 25 to house auxiliary equipment for the boiler such as a feed water sump 29 which may be mounted upon a platform 30 carried by the base frame legs 27 in spaced relation to the floor 28. A water supply pipe 31 leads to the sump 29 and is controlled by suitable float valve mechanism 31^a to maintain a substantial fixed level of water within the sump. From the sump, water is conveyed to the drum 15 through a delivery or feed duct 32 which discharges through the bottom 15^b and has its outlet end located a substantial distance above said bottom so as to project above mud that may accumulate thereon.

A constant head or body of water, partially filling the drum 15 is maintained by means of an intermittently operable feed pump 33 of suitable design suitably interposed in the feed water duct 32. A check valve 34 in the feed water duct prevents reverse flow of water from the drum 15. When the water in the drum 15 falls below a fixed

level which is indicated at 35, suitable regulating means will be operated to effect operation of the pump 33, such means in the present instance being electrically controlled responsive to fluctuations in the water level and including a driving motor 31 for the pump.

An electrical control circuit for the feed pump motor 37 may include an electrical lead 38 having a relay 39 therein and connected at one of its ends to an electrode 40 mounted within a small water regulator tank 41 and at the same height as the preferred water level 35. The inner end of the electrode 40 may be in spaced relation to the wall of the tank 41 which is suitably grounded and an electrical circuit through the electrode 40 and the tank serving to cut out the motor 37 is completed only when the water is at the proper level. For this purpose the tank 41 may be connected in suitable manner to a conventional stand pipe 42 which in turn communicates at its upper and lower ends with the interior of the drum 15 through the top 15^a and the bottom 15^b, respectively. Thus, when the water level 35 drops, a corresponding drop will take place in the regulator tank 41, opening the motor cut-out circuit through the electrical lead 38 so that the water pump motor 37 will operate to drive the water pump 33 and thereby "make up" or replenish the supply of water in the drum 15. The stand pipe 42 may also carry a conventional water gauge 43 and a pressure gauge 44, as well as any necessary valves 44^a.

According to the present invention forced cyclical circulation of the water is effected from the drum 15 through the pressure duct 17 and the heating tubes 18 and back through the drum. To this end the duct 17 has a suitable circulating pump 45 connected therewith and adapted to be actuated by a suitable power means such as a motor 37. Similarly as the feed pump 33 and its motor 37, the circulation pump 45 and its motor 37 may be mounted upon the lower platform 30 of the base under the steam generating apparatus and high enough off of the floor 28 to permit cleaning thereunder as by means of a stream from a water hose. A tubular outlet 46 projects upwardly through the bottom of the drum 15 substantially above the mud sump area to withdraw and conduct the water from the drum to one side of the pump 45 from which the water is forced at a predetermined velocity through the remainder of the pressure duct 17 and then through the heating tubes 18 wherein the heat of the combustion gases from the burners 19 is transferred to the water, the water thereafter being returned to the drum 15. A suitable shut-off valve 47 for segregating the pump 45 may be located in the outlet 46 to be manually controlled by a conveniently located handle 47^a. A suitable one-way automatic check valve 47^b may be provided in the lower end of the riser of the pressure duct 17 to segregate the pump 45 therefrom.

Both the circulation force pump 45 and the feed water pump 33 have double stroke action.

In the preferred operation of the present steam generating system the water drawn from the drum 15 is impelled through the heating tubes 18 by the circulating pump 45, supplemented by acceleration due to periodic steam expansion, at such a velocity and in such volume that only enough heat will be absorbed by the water to convert a small fraction of the water into steam in any one circulation cycle. I have found that the greater the velocity at which the water is

circulated through the heating tubes while maintaining a constant volume, consistent, of course, with economical pumping, the higher will be the efficiency of the system. Goods results have been obtained in practice by forcing the circulation with such velocity that no more than one part in about three of a unit volume of the water will be converted into steam in one circulation cycle, the velocity in the heating tubes being roughly six hundred feet per minute. In any event the velocity should preferably be such in the tubes that due to the speed of flow and the pressure created there will be relatively little steaming in the tubes but only heat absorption, the breaking into steam occurring mainly when the pressure is relieved outside of the tubes. Thus, it is possible to circulate water continuously from and back to the drum 15 with a minimum of steaming until the water is returned from the heating tubes to the drum. It will be understood, of course, that steam formation in the heating tubes may be entirely eliminated if desired by suitable increasing the water pressure or velocity or both.

In the present instance, however, the pressure upon the water is periodically interrupted in the circuit by diverting it from the tubes and then causing it to flow on through succeeding tubes of increased cross-sectional flow area to accommodate expansion arising from steam formed incident to the pressure drops. Preferably, however, the increase in flow area of successive tubes or banks of tubes is somewhat less than the theoretical amount required to accommodate the full expansion of the circulating water so that the velocity of the water through such tubes increases progressively. This increase in velocity compensates for the rise of temperature of the water and thus provides substantially uniform heat absorption throughout the entire series of tubes.

As herein shown, the enlarged flow area is attained by constructing the heating tubes 18 not only to carry the water therethrough in a continuous series, but also in parallel passages increasing in number as periodic steaming expansion occurs. To this end the heating tubes 18 preferably comprise tubing of uniform pipe size formed into a plurality of individual, cylindrical helical coil sections of such varying diameters and length that they can be mounted in concentric closely adjacent relation to form a generally cylindrical mass of substantially uniform over-all length. The loops or helices of the individual coil sections are preferably uniformly spaced one from the other and are held against springing by circumferentially spaced vertical rows of fixed heat-conducting spacers 86. In the assembly, the helices of each coil section are preferably placed in as nearly equally spaced closely staggered relation as possible with respect to the helices of the immediately adjacent coil section or sections (Fig. 2). Due to this closely staggered relationship of the coils, practically every particle of the heated gases from the burners 19 that passes through the heating coil assembly will be baffled to travel in a turbulent circuitous path and be in practically continuous intimate heat transfer relation to coil helices from end to end of the coil assembly. Moreover, because of the fairly dense mass of the heating coils there is a throttling effect upon the heated gases which slows their travel sufficiently to assure all possible heat abstraction by the water-swept coils. In spite of such throttling of the

gases, however, no portion of any heating tube throughout the tube assembly will overheat because the high velocity water cools all portions equally. In fact, the temperature of those portions of the tubes subjected to the greatest heat will be substantially the same as at the point where the spent gases pass off.

In the embodiment of the invention illustrated, there have been provided nine coil sections of equal pipe size and of graduated diameters, progressively diminishing in pipe length corresponding to decrease in diameter so that each section may have nine equally spaced loops or helices in a predetermined standard length coil cylinder. These nine coil sections have been divided into three successive passes or banks connected in series to conduct the boiler water progressively from the outside to the inside of the cylindrical coil assembly. Thus, the boiler water is delivered by the pressure duct 17 first to a pair of outermost coil sections 87 for travel therethrough in parallel paths, and is thence conducted through three parallel-flow intermediate coil sections 88 whence it will be conducted into four parallel-passage inner or final heating coil sections 89. The coil assembly is preferably located in closely embracing, concentric relation to the upper portion of the drum 15 so that the combustion gases must pass upwardly therethrough from the burners 19. Furthermore, in order to secure the utmost thermal efficiency the water is caused to flow through each successive bank of coils from the top downwardly, counterflow to the upflowing hot combustion gases. Through this arrangement, by utilizing approximately four hundred feet of standard three-eighths inch or one-half inch tubing in the heating coil assembly, may be had a steam generator of at least forty-five horse power normal capacity.

As a result of the counterflow of water and its high velocity heat will be practically exhausted from the combustion gases before they leave the heating coil assembly. However, the capacity for heat abstraction from top to bottom of the coil assembly will be almost uniform because of the continuous velocity of the water. Moreover, the increased heat transfer area of the successive banks of coils and the acceleration of velocity assures uniformity of heat abstraction horizontally through the mass of coils. Another factor to be noted in this connection is that the progressive reduction in the lengths of the coils of the individual coil sections from the outer to the innermost due to diminution in diameter, and thereby graduated reduction in heat transfer area, is compensated for by the successively increased number of coil sections in the banks of coils and also by the increased velocity of the water through the successive banks of coil sections. All of these observations have been determined from critical inspection and analysis in actual operation of the invention. If graphically represented, the heat absorption rate "curve" taken in any horizontal or vertical plane through the coil assembly would be almost flat, showing uniform abstraction of heat from the combustion gases from the outermost to the innermost coil section and from top to bottom of the coil assembly.

Each of the cylindrical-coil heating tube sections is preferably individually supported so that it can be removed from the assembly substantially without interfering with or interference from the remaining coil sections, and yet all of the

coil sections are preferably supported to be handled as a complete unit. To this end the coil sections may be suspended individually from a supporting frame preferably comprising a pair of spaced parallel horizontal beams 91 which may be detachably carried by the drum 15 as by bolting the same to angle brackets 92 upon the drum top 15a. Cross bars 93 may connect the beams 91 into a rigid framework.

To connect the heating coils to the supporting beams 91, detachable hangers 94 (Figs. 2, 3 and 4) preferably in the form of non-corroding metal straps, are provided. These straps are looped over the beams and under the uppermost loops of the respective coil sections, and have their respective ends connected together as by means of bolts 95 so that they can be easily removed. Preferably, four of the hanger straps 94 are provided for each coil section, one at each of the four points where the latter underlies the supporting frame beams 91. Thus, when it is desired to remove the heating coil assembly 18 as a unit, it is merely necessary to detach the beams 91 from the angle brackets 92 and lift the supporting frame and the entire heating coil assembly upwardly away from the drum 15. Then any individual tube section can be removed merely by disconnecting its four hanger straps 94 from the supporting frame.

Delivery of the pumped water from the pressure duct 17 to the outer or first bank of heating coil sections 87 may be effected through an equal-flow branch divider 96 (Figs. 1 and 4). Transfer from the first bank to the intermediate bank coil sections 88 may be effected through a suitable upright header 97 to the lower end of which the discharge ends of the coil sections 87 are connected by suitable unions and to the upper end of which the inlet ends of the coil sections 88 are connected, also preferably by suitable unions. In like manner, an upright header 98 may be provided for effecting transfer of the circulating water and steam from the intermediate bank coil sections 88 to the last bank of four coil sections 89. From the latter coil sections the water and steam are conducted through a preferably L-shaped vertical and horizontal header 99 to the inlet end of the steam separating member 20.

Because water abstracts heat readily compared with steam, several measures in addition to the forced circulation are taken herein to assure constant and accelerating velocity of the water through the heating coils and freedom from stagnation or striation therein so that the heating surfaces will be constantly swept by water, and steam will be prevented from collecting in masses or patches but will, if it is present at all, be carried by the water in the form of small, well distributed bubbles. For example, tubing of relatively small diameter is used in the heating coils to provide a relatively large heat transfer surface and to insure high velocity of the water through the tubes. Such tubing is also advantageous by reason of the lower cost per unit area of heating surface.

Furthermore, the headers 97 and 98 by their positions and the angle of entry of the heating tubes will cause a mixing action of the entering streams of water due to the abrupt commingling and change in direction of flow. In addition, these headers are preferably of greater cross-sectional flow area than that of the banks of coils to which they respectively deliver, and by the same taken, are of substantially greater cross-sectional flow area than the coils from

which they receive, thus effecting additional agitation and turbulence of the entering water due to expansion from steaming arising from the reduction in pressure, the steam being thoroughly broken up into tiny bubbles. Then, upon delivery of the steam and water mixture to the succeeding coils, there will be an acceleration of velocity because of the steam expansion and the reduced cross-sectional flow area of the receiving coils compared with that of the header. Final steaming may take place in the last header 99 and in the steam separator 20 which are preferably of greater cross-sectional flow area than that of the four coil sections 89 of the last bank combined. Due to the steaming and deceleration of the water in the header and the separator, some deposition of minerals may occur therein but this will not be great nor interfere with the optimum efficiency of the boiler as a whole. In any event, the deposits can easily be cleaned out of the headers on occasion.

Herein the steam separating member 20 serves the double function of separating the steam which has been generated and also of returning the unconverted water to the main body of water within the drum 15 substantially without agitation or foaming. In the preferred form, the member 20 is of elongated tubular shape and has a cross-sectional flow area at least as large or slightly larger than the cross-sectional flow area of the header 89. Therefore, the steam can expand within the member 20 and may easily be separated from the unconverted water. For separation the steam may escape from the member 20 through a longitudinal series of openings 100 such as transverse slots formed in the wall thereof. Also, the separator 20 preferably extends downwardly longitudinally within the drum 15 adjacent to the vertical wall thereof, and the steam escape slots 100 are directed toward such wall in the space above the water level 35 so that water carried therethrough by the steam will impinge against the drum wall and flow circumferentially and downwardly therealong into the main body of water without agitation. Such impinged water will cool the drum wall by absorbing some of the limited amount of heat derived from the combustion gases passing upwardly through the adjacent portion of the coil assembly 18, some of the water being thereby converted into steam and the remainder aiding in preheating the main body of water to which it returns.

Rolling of the main body of water in the drum 15 by the water returned through the member 20, is avoided by having its discharge or outlet end 101 project below the water level 35. In addition, the discharge or outlet end 101 is preferably constructed to direct the discharging water toward the side wall of the drum and may for this purpose be formed on a bias as shown (Fig. 2). It will be evident also that due to the release of pressure by the separation and escape of steam through the steam slots 100, the unconverted water will discharge from the outlet 101 without substantial force.

Since the steam is effectually separated from the unconverted water in the steam chest space in the upper portion of the drum chamber 15, the steam can be withdrawn in water free condition through a main 102 which communicates with the steam chest space through a port 103 in the drum top 15a. The steam escape openings 100 of the steam separator are preferably directed to the opposite side of the steam separator from the port 103 and are in such spaced relation to

the latter that even at peak demands water which may escape from the openings 100 will not be drawn into the steam main 102. Steam that may possibly arise from the main body of water in the drum 15 cannot cause surging of such water from the water level 35 to the steam withdrawal port 103 due to the substantial intervening space. Should the steam pressure within the drum 15 become excessive, it may be released through a suitable automatic safety valve 104.

The unconverted water which is returned from the steam separator 20 to the drum 15 serves as a preheating medium for the reserve supply of water within the drum and particularly for the make-up water which is supplied through the feed duct 32. In addition to such preheating of the water supply internally, external heat is transferred through the enclosing wall of the drum 15 by radiation from the burners 19. In the full running condition of the boiler the preheating may aggregate close to the critical temperature of the water so that most of the heat absorbed by the water in passing through the heating tubes 18 will go to raise steam.

As shown, the burners 19 are of a suitable gas fired type supplied from a manifold 105 concentric with the drum cradle 23 (Figs. 1, 2 and 7) and are preferably equidistantly spaced from one another and uniformly spaced from the vertical wall of the drum 15. The tops of the burners 19 are located at a predetermined distance above the drum bottom 15b but substantially spaced from the lower loops of the heating coil assembly 18, thereby providing a substantial combustion space or chamber 107 defined herein in part by the tops of the burners, the vertical wall of the drum 15 and the bottom row of loops of the heating coils. A large percentage of laterally radiated heat from the burners 19 will therefore impinge upon and be transferred to the boiler water through that portion of the drum wall which is exposed to the combustion chamber 107, without abstracting any appreciable heat from the gases of combustion which pass up toward the heating tube assembly 18. Preferably the water level 35 in the drum is above the lower row of heating coil loops so that all of the wall area of the drum subjected to radiated and convected heat below the coils will be adequately cooled. That portion of the drum which lies below the tops of the burners will remain substantially unheated, with the water therein practically stagnant, and therefore will serve effectively to collect the material or mud deposited from the water heated in the preheating zone thereabove, the thoroughness of the preheating assuring that most of the mineral matter and suspended material in the water will settle out in the drum.

Fuel from a suitable source is supplied as by means of a gas main 108 which communicates with the manifold 105 and may be provided with a gas regulator 109 which will be responsive to steam pressure within the drum 15. To control the gas regulator 109 a pressure duct 110 may lead therefrom into communication with the water-gauge stand pipe 42.

A low water shut-off valve 111 may be interposed in the gas main 108 as a safety measure to discontinue the gas supply to the burners should the water feed to the drum 15 accidentally stop during operation. Suitable means for controlling the shut-off valve 111 automatically may comprise a solenoid 112 having a grounded circuit including an electrical lead 113 connected with an electrode 114 near the bottom of the water regulator tank 41 so that when the water

therein falls below the safety level, the shut-off solenoid 112 will operate to close the valve 111 and stop the burners 19 to halt operation of the boiler. The solenoid 112 or other suitable gas controlling means may be utilized to shut off the gas supply if the water circulation pump 45 should stop or for some reason fail to circulate the water properly. A suitable pilot 115 communicating with the gas main 108 ahead of the shut-off valve 111 may be provided for lighting the burners.

Instead of the gas burners 19 suitable oil consuming burners may be relied upon as the heat source for the present boiler. For example, a blower-type of fuel oil burner may be mounted to fire substantially tangentially into the combustion chamber 107.

Combustion air is supplied to the burners 19 through the platform 25 of the base framework 16. This air will be more or less preheated by the heat thrown off by the pump motors, the circulation force pump 45 and the various pipe connections which conduct the preheated water from the drum 15 to and from this pump. To assure absorption of such heat by the air, the base framework may be substantially enclosed except under the burners 19 by a sheet metal sheath or casing 117 which may include removable side panels 118 of which at least the one nearest the circulation pump 45 may for induced or natural draft conditions be provided with louvers 119 for admitting air into the base enclosure. The removable panels 118 may be hinged, or removably hung upon hooks 120 projecting outwardly from the edge of the platform 25, and may be secured in place by means such as thumb screws 121. Where a forced draft is desired in the boiler unit, instead of a natural or induced draft through the louvers 119, a suitable fan (not shown) may be supplied in one side of the base 16.

Enclosing the combustion chamber 107 and the heating tube assembly 18, is a suitable casing 122 which in the present instance is preferably constructed of a plurality of removable sections each of which is adapted for independent removal for access to the adjacent portion of the steam generating unit. Accordingly, the casing may comprise substantially equally divided upper and lower annular cylindrical portions, the lower of which is divided into semi-cylindrical separable front and rear sections 123 and 124, respectively, and the upper of which is divided into semi-cylindrical front and rear sections 125 and 126, respectively. Each of the casing sections 123, 124, 125 and 126 is preferably of a substantially standardized construction and a description of one section will therefore suffice for all. Thus, each section includes an inner shell member 128 and an outer shell member 129 (Fig. 4) having suitable insulating material therein and separably connected together in spaced parallel relation by means of properly dimensioned coactive outwardly projecting flanges 130 and 131, respectively, at their vertical edges and similar coacting flanges 132 and 133, respectively, at their horizontal meeting edges.

In assembly, the lower casing sections 123 and 124 rest upon the base platform 25 and have their vertical edges connected together detachably as by means of bolts 134 which pass through the outer margins of all of the conjoined flanges 130 and 131. The upper casing sections 125 and 126 rest upon the upper edges of the lower casing sections 123 and 124 and are removably secured thereto as by means of bolts 135 passing through

the exposed margins of the conjoined horizontal flanges 132 and 133. The conjoined vertical side flanges of the upper sections may be secured together similarly as the corresponding flanges of the lower sections. Through this construction it will be apparent that any one or more of the semi-cylindrical casing sections may be removed without disturbing adjacent sections of the casing or the insulation therein, and if access is desired into one of the casing sections, it is merely necessary to remove the outer shell 129 thereof.

Preferably, the space between the casing shells 128 and 129 wherever convenient, is utilized for such vertical connecting piping as the pressure duct 17, and the headers 87, 88 and 89. Access to such piping can be had readily by removal of the enclosing outer casing shell 129. Preferably, suitable unions are utilized in connecting such piping so that it can be easily removed when necessary.

A removable top closure for the casing is provided in the present instance by a double-walled, insulated disk-like member 137 dimensioned to fit relatively snugly into the cylindrical opening defined by the upper margins of the upper casing sections 125 and 126 and supported by an inwardly projecting shoulder flange 138 carried by said sections. Opening through the top member 137 is a flue outlet defined by an upwardly projecting flue collar 139 which is adapted to receive a suitable flue pipe 140. When access into the top of the casing is desired, the top closure member 137 can easily be lifted away.

Preferably, the internal diameter of the upper portion of the casing 122 relatively closely approximates that of the outermost heating tube section 87 so that upward passage of the flue gases will be closely confined to travel between the coils. Moreover, the enclosure provided by the lower portion of the casing about the fire box 107 will reflect and radiate toward the preheating zone of the drum 15, heat which impinges upon the inner wall of the lower casing sections 123 and 124 by radiation from the burners 19. To aid in this, the lower casing sections may be provided with polished reflective surfaces to throw the heat inwardly toward the drum. Similarly, the upper casing sections may be thus equipped to retain the heat within the upper part of the casing chamber.

If it is desired to utilize more fully the heat radiated toward the inner walls of the lower casing sections 123 and 124, the outer two coil sections 87 which comprise the first bank of the heating coil assembly 18, may be increased in length to extend downwardly substantially as shown in Fig. 5 along the inner walls of the lower casing sections into the radiated heat zone. Thereby, practically no radiated heat will be lost and the confining walls of the lower casing sections will be protected against overheating and the best part of the radiated heat which is not utilized for preheating the water in the drum 15 will be used in generating steam.

Superheated steam may be produced by passing the steam from the live steam main 102 through a downcomer 141 which is preferably enclosed within the inner and outer shells of the casing 122 and which communicates with a superheater 142 as shown in Figs. 6 and 7. This superheater is preferably constructed of a plurality of loops of pipe 143 each individually communicating with the downcomer 141 and conducting the steam in parallel paths around the

interior of the lower casing sections 123 and 124 within the most active portion of the laterally radiated heat zone of the burners 19. After traversing the superheating circuit through the loops 143, the superheated steam may pass therefrom into a superheated-steam main 144.

From the foregoing it will be apparent that the invention provides a novel method of generating steam wherein the boiler water is continuously circulated at high speed in a cycle which carries it in contact with the heating surfaces in such volume and at such velocity that only a small proportion of the water is converted into steam during any one circuit through the system. In the steam generating phase of the circulation cycle, the increasing velocity of the expanding steam and water and the frequent agitation to which the water and steam mixture is subjected effectively avoid stagnation and striation at any point, thus assuring an exceedingly high rate of heat absorption, keeping the heating surface uniformly cool and free from sedimentation or scaling or danger of overheating or burning out. Steam separation is effected in a highly advantageous manner which avoids passage of water into the steam main and effects a return of the unconverted water quietly and without rolling of the water reserve which the returned water serves to preheat. Radiated as well as convected heat is used to utmost advantage in generating steam as well as in preheating the boiler water, and even the heat from the auxiliary equipment of the boiler is not wasted but is utilized for preheating the air for the burners.

It will be apparent that in generating steam in accordance with the above method the efficiency of the generating unit can be maintained substantially uniform throughout its entire operating range. Due to the accurate control of circulation provided, the rate of flow of water over the heat transfer surfaces can be regulated so as to provide the optimum rate of heat absorption for any rate of heat input. Thus, when the unit is operated at maximum capacity, that is, when the maximum amount of heat is supplied, the rate of circulation may be increased by speeding up the circulating pump. On the other hand, when the heat supply is reduced, the rate of circulation may be correspondingly reduced so that the conversion efficiency remains substantially at the maximum point.

To practice the novel method, a new self-contained automatic steam generator has been provided which is exceptionally economical in floor space and headroom since the whole unit can be embodied in a small vertically arranged structure in which practically all of the auxiliary equipment is housed within the base under the steam generating part of the unit. No special settings or boiler pit are required, but the unit can be placed wherever the small amount of room required is available therefor, and where it is gas fired it need not even be connected with a stack, because where no stack is available for inducing natural draft, forced draft may very easily be applied. Because of the negligible exterior temperature of the outer casing the unit can be housed in places not ordinarily practicable for a boiler. But one drum is required and that will serve as a combined water reservoir, preheater, mud drum, steam separating chamber, and steam chest. In addition, the drum supports the heating tube assembly from which any one of the plurality of tube sections can be easily removed if necessary without altering the suspension of any

of the other tube sections. The casing which encloses the unit can easily be opened by the removal of selected sections for access into any portion of the unit. Other parts of the unit are also easily removable. Withal the unit is adapted for unusually long periods of continuous operation at high output with undiminished efficiency and without requiring special attention. Ample safety features are embodied in the unit to avoid danger of overheating should any vital mechanism fail; and although it is hardly likely that any heating tube coil should ever burn out or break, yet if it does no danger will be encountered from escaping steam due to the very limited amount that would be released.

As a practical example, an actual installation embodying the principles of the invention in a steam generating unit approximately thirty inches in diameter upon a base three and one-half feet square and having an over-all height of about five and one-half feet has been operated over an extended period to generate about one thousand pounds of steam per hour continuously at a normal working pressure of about one hundred twenty-five pounds per square inch and a maximum of two hundred fifty pounds per square inch. This unit has an over-all thermal efficiency averaging eighty-five percent, without the use of a preheater or economizer, and has unusually large overrating since it generates one boiler horsepower for about every one and one-half square feet of heating surface. The steam and water drum of this unit is a tube of ten inch diameter providing a water reserve of about six gallons while the heating coils comprise a total of about two hundred fifty lineal feet of one-half inch standard pipe size seamless tubing having, together with the accessory piping, a capacity of about an additional six gallons. Due to the high velocity of water through the tubes, namely, such as to effect a complete turnover of water in the entire system every two minutes, the heat transfer constant, that is, the ratio of heat transfer per unit area of the tubes, taking into consideration the thickness and temperature difference of the material forming the same, has been about fifty as compared with a range of from three to fourteen customarily found in the heat transfer surfaces of prior water tube boilers. The actual temperature of the tubes at any point in the assembly has been found to be just a few degrees above the temperature of the fluid flowing therein. In this unit, the water has been circulated at approximately three times the maximum speed of evaporation. Over an extended period of time sedimentation or scaling in the heating tubes has been negligible and no cleaning has been required although untreated relatively hard water has been used. Oil in the water, as may come from the circulation pump, has no detrimental effect upon thermal efficiency of the unit, the volatile constituents apparently passing off with the steam and the remaining sludge collecting in the mud sump of the water drum. Sedimentation has been almost completely confined to the bottom of the central drum from which the muddy deposit is blown off at intervals. In operation this unit has been almost perfectly silent. In commencing operation from a cold state, the burners can be at once fired fully without in anywise endangering any part of the unit and a full head of steam has been obtained within a few minutes after starting.

I claim as my invention:

1. A steam generating unit comprising, in com-

bination, a base, an elongated drum supported in a vertical position on said base, a heating tube assembly encircling the upper portion of said drum, combustion means disposed in heating relation to said drum and to said tube assembly, a casing enclosing the drum, the combustion means and the tube assembly for confining the products of combustion to an upward path through the tube assembly, means for feeding water into said drum including a pump and control means therefor operative to maintain a predetermined level of water within the drum rising at least as high as the bottom of said tube assembly, means for circulating the water from said drum through the tube assembly including a pump operative to force the water through the tube assembly at a predetermined velocity, both of said pumps being of double stroke action adapted to pump the water with substantially continuous pressure and without surging, and a connection from said tube assembly to the upper portion of said drum for returning the water to the drum after its passage through the heating tube assembly.

2. A steam generating unit comprising, in combination, a cylindrical water drum, a series of concentrically coiled tubes encircling the upper portion of said drum, said tubes being arranged in groups having progressively increasing over-all cross-sectional areas, headers connecting adjacent groups of tubes to provide a continuous flow passage communicating with the upper portion of said drum, means for heating said drum and said tubes, means for supplying water to partially fill said drum, and a pump arranged to withdraw water from said drum and to circulate it through said tubes at such a velocity and in such volume that only a relatively small portion of the water is converted into steam upon its return to the drum, the remainder of the returned water being mixed with the water in the drum for recirculation through said tubes.

3. A steam generating unit comprising, in combination, a base, a vertically disposed water drum, a heating tube assembly surrounding the upper portion of said drum, means supporting said tube assembly on the drum, heat supply means disposed in heating relation to said drum and said tube assembly, a feed pump for supplying water to said drum, and a pump for circulating water from the drum through said tube assembly and back to the drum to convert a portion of the water into steam, said drum, said heat supplying means and said pumps being mounted on said base to form a unitary structure.

4. A steam generating unit comprising, in combination, a base, an elongated drum supported in a vertical position upon said base, a heating tube assembly encircling the upper portion of said drum, said tube assembly communicating with the upper portion of said drum, combustion means disposed below said tube assembly in heating relation to said drum and to the tube assembly, a casing enclosing the drum, the tube assembly and the combustion means operative to confine the products of combustion to an upward path along the sides of said drum and through said tube assembly, means for supplying water to said drum, a pump for forcefully circulating the water from said drum through said heating tubes and back to the drum to convert a portion of the same into steam, and means in said drum for separating the steam from the water returned thereto.

5. A steam generating unit comprising, in combination, a water chamber, means for supplying water to said chamber, a plurality of concentric helical heating coils encircling said chamber and connected therewith, said coils being arranged in groups of progressively increasing aggregate flow area to accommodate steam expansion, headers connecting successive groups of coils to provide a continuous passage for water to be converted into steam, means for heating said coils and said chamber, power actuated means for withdrawing water from said chamber and forcibly circulating it through said coils to absorb the heat imparted to the coils by said heating means whereby to convert a portion of the water into steam.

6. A steam separator for a steam generating unit wherein the water is heated to steaming temperature and delivered into a partially filled water drum, said separator comprising an elongated hollow member having its discharge end adapted to project into the body of water within the drum and a plurality of steam escape openings in the form of transverse slits disposed in longitudinally spaced relation in the wall of said member to permit escape of steam from the water passing therethrough before the water reaches said discharge end.

7. A steam generating unit including, in combination, a heating coil assembly of generally cylindrical form and comprising a plurality of concentric coil sections, said coil sections presenting a progressively diminishing heat transfer area from the outer to the inner section, and means connecting said coils into a continuous series of unidirectional parallel-flow banks progressively increasing in number of coils from the outer to the inner bank so as to provide substantially equal heat transfer areas for each of said banks.

8. In a steam generating unit, in combination, a heating tube assembly comprising a plurality of concentric coils of tubing, headers connecting said coils in groups progressively increasing in number of coils per group to provide a series of parallel flow passages, means for passing gases over said coils in one direction, and means for circulating water through the passages provided by said groups of coils counterflow to the passage of heated gases over the coils to absorb the heat imparted thereto by the gases.

9. A steam generating unit comprising, in combination, a base structure including a raised platform, heat transfer means above said platform including a water reservoir, a burner mounted on said platform for heating said heat transfer means, means for circulating the water from said reservoir through the remainder of said heat transfer means including a pump housed under said platform, means for drawing combustion air for said burner over said pump to cool the same and to preheat the air.

10. In a steam generating unit, in combination, a source of heat, a plurality of heating tubes arranged in heat absorbing relation to said heat source in groups providing a series of banks of parallel flow passages of progressively increasing flow area, means for circulating water through the tubes for partial conversion into steam, and headers connecting each bank of tubes with the succeeding bank positioned to effect an abrupt change in the direction of flow of the entering water and steam mixture, each of said headers having a greater flow area than the bank of tubes to which it discharges so as to permit a partial conversion of the water into

steam and thus effect delivery of the steam and water mixture to the succeeding bank of tubes with increased velocity.

11. A steam generating unit comprising, in combination, a vertically mounted combined water reservoir and steam separating drum, means for supplying water to fill said drum only partially, a plurality of concentric helical heating coils encircling the upper portion of said drum, said coils being arranged in a series of successive groups of progressively increasing aggregate flow area, means for supplying heat adjacent to the lower portion of said drum for preheating the water therein and for heating said coils, means for withdrawing water from said drum and forcibly circulating the water through said coils, means forming at least part of the flow path from group to successive group of said coils constructed and arranged to permit limited flashing of steam to boost the speed of water flow through the successive group of coils, and means connecting the group of coils through which the water flows last with the top of said drum for separating steam from the water.

12. A steam generating unit comprising, in combination, a water chamber, means for feeding water to said chamber to maintain a substantially constant level of water only partially filling the chamber, a continuous series of heat transfer coils surrounding the unfilled portion of said chamber while leaving the lower portion of the chamber free, one end of the series communicating with the water-filled portion of said chamber to receive water therefrom and the other end of the series communicating with said unfilled portion to discharge the water thereinto, means for forcibly circulating the water through said coils, and means for simultaneously heating the water-filled portion of said chamber and said coils.

13. A steam generating unit comprising, in combination, an upright drum, means for maintaining a body of water partially filling said drum, a casing enclosing said drum in radially spaced relation, a massed series of heating tubes substantially filling the space between said casing and the upper unfilled portion of said drum, a heat source under said heating tubes in the space between said casing and the lower water-filled portion of said drum for preheating the water in said drum and for heating said tubes, said tubes being arranged to force the heat from said source to travel upwardly in sinuous paths

therethrough and serving to protect said upper unfilled portion of said drum against overheating, and means for connecting one end of said series of heating tubes for receiving water from the body of water in said drum and the other end of the series for discharging the heated water into the upper unfilled portion of the drum for separation of steam.

14. A steam generating unit comprising, in combination, an upright drum, means for maintaining a body of water partially filling said drum, a casing enclosing said drum in radially spaced relation, a mass of heating tubes substantially filling the space between said casing and the upper unfilled portion of said drum and leaving the lower water-filled portion free, a heat source under said heating tubes in the space between said casing and said lower water-filled portion of said drum for preheating the water in said drum and for heating said tubes, said tubes being arranged to force the heat from said source to travel upwardly in sinuous paths therethrough and serving to protect said upper unfilled portion of said drum against overheating, means for connecting said heating tubes for receiving water from the body of water in said drum and for discharging the heated water into the upper unfilled portion of the drum for separation of steam, and a superheater comprising an arrangement of coils mounted adjacent to said casing opposite the water-filled portion of said drum and below said heating tubes connected to receive steam from the upper unfilled portion of said drum and adapted to be heated by radiated heat from said heat source.

15. In a steam generating unit, in combination, a heating tube assembly comprising a plurality of tubes arranged in concentric coils, means for supplying heat to said tube assembly, power actuated means operative to forcibly circulate water through the tube assembly, and headers connecting successive coils from the outside to the inside of the assembly in series by groups to provide a plurality of banks of parallel flow passage, each of said headers providing a larger cross-sectional flow area than the tubes from which circulating water is supplied thereto so as to permit a partial conversion of the water into steam with resultant expansion whereby the water is delivered to the succeeding tubes with increased velocity.

CHADWELL O'CONNOR.
